UNITED STATES PATENT OFFICE.

HENRY CORTELYOW, OF FAIRLAND, INDIANA, ASSIGNOR OF ONE-HALF TO
FRANK CHAPMAN, OF SAME PLACE.

STRAW-STACKER.

SPECIFICATION forming part of Letters Patent No. 257,556, dated May 9, 1882.

Application filed December 27, 1881. (No model.)

To all whom it may concern:

Be it known that I, HENRY CORTELYOW, a citizen of the United States, residing at Fairland, in the county of Shelby and State of Indiana, have invented certain new and useful Improvements in Straw-Stackers; and I do declare the following to be a full, clear, and exact description of the invention, such as will enable others skilled in the art to which it app pertains to make and use the same, reference being had to the accompanying drawings, and to the letters and figures of reference marked thereon, which form a part of this specification.

My invention relates to means for carrying and distributing straw to stacks, as it is delivered from the apron of thrashing-machines; and it consists in details of construction and arrangement of parts that will be hereinafter more fully set forth in the specification and claims and pointed out in the accompanying drawings, in which—

Figure 1 is a perspective view of my device. Figs. 2 and 4, front elevations; Fig. 3, a side elevation of devices when folded; Figs. 5 and 6, a plan view and section, respectively, of the turn-table, and Fig. 7 a detail view of the device for adjusting the pulleys.

The object of the invention is to provide a simple and compact portable device that is easily and quickly put in position by one man, and one in which all cog-wheels are dispensed with, thus removing all danger of clogging and breaking.

The device is particularly adapted for use in connection with the portable thrashers now in general use.

Referring more particularly to the drawings, A B represent the running-gear, having mounted thereon a folding derrick made in two parts, D D', hinged at d, and provided with fastening-hooks or other suitable holding devices, b. These uprights are let into the cross-piece C, secured to the sides A by bands e, the cross-piece being notched or shouldered for that purpose, so that the piece C can easily turn. The uprights are held in position and prevented from swaying by the guy-ropes F'.

Secured to and supported by the frame A is a folding frame, hinged to A at w', and held in its upright position by catches T, secured to a fixed vertical frame, S, on the running-gear. This frame supports a turn-table consisting of

two circular pieces, M N, one of which turns about the other. A shaft, L, carrying a pulley, P, is secured to the outer or movable piece, N, by straps k', and enters the upright pieces K, which support the receiving end of the straw-carrier. This shaft L also passes through the outer pulley, O. The pulley P is connected by a band, P', to a pulley, Q, on the shaft X, which passes through the pulley R, connected by a band with the thrasher engine or motor. Thus the same power that operates the thrasher operates the stacker. The upright pieces V of the folding frame are slotted for the reception and play of springs u', upon which the shaft X rests. (See Fig. 7.) This shaft (and therefore the pulley Q) is adjusted vertically by means of hook-pieces V', which pass through the cross-bar V'' of the folding frame, and have underneath a rubber washer, W, held in place by a nut. If at any time the band P' becomes too tight or too loose, it may be adjusted by unscrewing or screwing up the nut against the washer, which acts to draw down or let up the pieces V' and shaft X without stopping the machine, the springs u' acting to force up the shaft when the nut is loosened, and also act as compensators for any sudden jerking or pulling of the band on the pulley.

The straw-carrier is supported by the uprights K on the shaft L, and consists of two pieces, I I', hinged together at i, and provided with the ordinary apron, J. The receiving end of the carrier is provided with a shield, J', to prevent the straw from the thrasher falling from the sides. The apron J is actuated by rollers O'' on a shaft connected with pulley O', which in turn is actuated by a band running over pulley O, which is actuated by pulley P, as before described. The inner end of the carrier is supported by the pieces K, while the outer end is supported by a rope, F, attached to a bail, H, pivotally secured to I' by hooks or small chains Z'. This rope F passes over a pulley, G, on the derrick, and thence to a drum, E, on one side of the derrick. The pulley G may be secured to the top of the derrick by a swivel, so as to allow it to turn freely when the carrier is turned. Fig. 1 shows my device raised and ready for use, and Fig. 3 shows it folded for transportation, the pole Z being hooked to the thrasher or engine and moved with it.

When the device is to be put in operation I move it near the rear end of the thrasher and raise the derrick, securing the folded pieces by the hooks *b*, then draw taut the guy-ropes 5 *F'* and hold them fast by pins driven in the ground. Next wind up cord *F*, so as to raise the outer end, *I*, of the carrier until it turns on its hinges and extends outwardly, the cord *F* being loosened as it commences to turn on 10 the hinges. Next raise the turn-table by drawing forward on the carrier, and secure it in a vertical position by means of the hooks or fastenings *T*. The carrier can now be raised to any desired inclination by means of the 15 winding-drum, which is held in position by any ratchet or stop device secured to the drum. The carrier of the thrasher discharges between the derrick-posts on the apron *J* of the straw-carrier. The straw can now be carried in any 20 direction for stacking by simply moving the end *I'* of the carrier, which turns the disk *N* of the turn-table, by means of the pieces *K* and shaft *L*. As the stack increases in height it is simply necessary to wind up cord *F*, and 25 raise the carrier as described, and when out of reach of the hand of the pitcher it can be moved by the fork. The end of the carrier is sufficiently removed from the derrick to give the carrier free play from side to side.

30 Now, when it is desired to stop work the operation of folding the several parts is as follows: Unloosen cord *F* and allow the carrier to descend to the ground. Then unloosen hooks *T*, which permits the folding frame with 35 table to fall forward. This also causes the part *I* of the carrier to be carried forward. Next wind up cord *F* until the carrier-piece *I'* is raised and turns over on *I*, as first described. Then unhook the pieces *D'*, and they 40 will fall forward. Next unloosen the guy-ropes *F'* and the pieces *D* will fall backward, and all will assume the relative positions shown in Fig. 3.

It will thus be seen that my device can be 45 raised or lowered and operated by one man, and as the several parts—viz., the table and the apron—are actuated by pulleys without the intervention of cog-wheels, there is no danger of clogging, and breakage is reduced to a minimum. This is a great advantage not only in 50 practical use, but in first cost of manufacture and in subsequent repairs. It is very easy to supply a band-pulley; but a broken cog-wheel necessitates taking the machine to a shop for 55 repairs, and castings are always expensive. The several parts are light and strong and the mechanism is very simple.

Having thus described my invention, what I claim as new, and desire to secure by Letters Patent, is—

1. In a straw-stacker, the combination of a hinged foldable derrick, the uprights thereof being made in two pieces, a carrier, a winding-drum, a pulley, and a rope, substantially as and 65 for the purpose set forth.

2. In a straw-stacker mounted upon and in

combination with a hinged foldable frame, a turn-table, as described.

3. The combination, in a straw-stacker, of a hinged foldable frame, a turn-table, and the 70 running-gear, substantially as shown and described.

4. The combination, in a straw-stacker, of a carrier, a turn-table, a foldable supporting-frame, and the running-gear, substantially as 75 shown and described.

5. The combination, in a straw-stacker, of a foldable frame, the running-gear, and two circular disks, one of which is movable about the other, substantially as shown and described. 80

6. A turn-table for straw-stackers, comprising a foldable frame and disks, as described, in combination with two pulley-shafts, one of said pulley-shafts passing through the foldable frame and the other being secured to one 85 of the disks, as shown and described.

7. The combination, in a straw-stacker, of a pulley-shaft, *X*, the foldable frame, and suitable means whereby said shaft and the pulleys connected therewith are adjustably mounted in 90 said frame, substantially as and for the purpose described.

8. The combination, in a straw-stacker, of a turn-table and a carrier made in two pieces, supported by and moving with the turn-table, 95 as described, a foldable derrick, pulleys, rope-drum, and rope, whereby the outer piece of the carrier may be raised and lowered by said rope, substantially as set forth.

9. In a straw-stacker, the combination of 100 the turn-table provided with two disks, and the driving-shaft, the running-gear, the carrier, made in two pieces, *I* *I'*, a rope, *F*, a pulley, drum, and the derrick, substantially as and for the purpose described.

10. In a portable straw-stacker, the combination of a folding derrick made in two parts, a folding frame, a turn-table, the running-gear, and a carrier made in two parts, the lower end of the derrick, when not raised, being adapted to fall back and rest on a support on the running-gear, the upper end falling forward and resting on the carrier, the outer end of the carrier falling forward on the inner end, and the table and frame folding forward 115 on the running-gear, substantially as and for the purpose set forth.

11. In a portable straw-stacker, the combination of a folding derrick and turn-table, provided with a movable disk, with a carrier made 120 in two parts and provided with an endless belt or apron and actuating-shaft, a driving-belt, and a pulley-shaft, *L*, secured to the movable disk of the turn-table, substantially as and for the purpose set forth.

In testimony whereof I affix my signature in presence of two witnesses.

HENRY CORTELYOW.
